UNITED STATES PATENT OFFICE

GEORGE B. NICHOLS, OF AKRON, OHIO, ASSIGNOR TO THE FIRESTONE TIRE AND RUBBER COMPANY, OF AKRON, OHIO, A CORPORATION OF OHIO

TUBE-END BUFFER

Application filed December 2, 1927. Serial No. 237,200.

This invention relates to devices for buffering or abrading devices for roughening the skived ends of rubber tubes to be spliced by cementing or vulcanizing the same together.

An object of the device is to provide means for rotatably supporting a mandrel on which the end of a tube to be buffed is positioned and for aligning said mandrel with respect to a buffering or abrading wheel. A further object is to devise means for aligning the mandrel for buffering either the external or the internal surface of a skived tube end.

The foregoing and other objects are obtained by the device illustrated in the accompanying drawings and described below. It is to be understood that the invention is not limited to the specific form thereof disclosed herein.

Of the accompanying drawings, Figure 1 is a side elevation of a device embodying the principles of the invention;

Figure 2 is a plan view thereof illustrating the mandrel supporting means in one position;

Figure 3 is a similar view, partly broken away, illustrating said means in another position; and

Figure 4 is a detail section of the tube mandrel.

Referring to the drawings, 10 is a base or table supported by a pedestal 11. A motor 12 is mounted on the table and serves to rotate a buffering or abrading wheel 13 carried on the end of its shaft 14 journaled in standard 15.

Bracket 16 is hingedly mounted with respect to table 10 by means of a vertical stud shaft 17 adjustably clamped in slot 18 in said table, said bracket having an arm or stud shaft 19 hinged thereto. A lug 20 on arm 19 projects

within the end of bracket 16 and abuts either of adjusting screws 21 or 21^a to permit a limited horizontal swinging movement, whereby a reciprocable mandrel 22 slidably journaled on the arm, (Figure 4), may be swung into either of two inclined positions with respect to the buffering wheel. Various sizes of mandrels may be provided for accommodating different sized tubes 23 to be buffed, those mandrels not in use being conveniently retained in suitable apertures 24 in table 10.

In operation, the externally bevelled or skived end 25 of tube 23 is placed over mandrel 22 and brought into buffering position by swinging arm 16 until the tube engages the buffering wheel 13. In order to align the bevelled tube end 25 with the wheel, arm 19 is inclined relatively away from the wheel with lug 20 abutting screw 21, as illustrated in Figure 2. The mandrel is then rotated by hand and also reciprocated slightly to bring all portions of the skived tube end into engagement with the rapidly rotating buffering wheel. An internally skived tube end 26 is similarly buffed by cuffing the same before it is placed on the mandrel. Since the bevel on this end tapers in an opposite direction from the external bevel, tube end 26 is aligned with the buffering wheel by swinging arm 19 relatively toward the wheel until lug 20 abuts screw 21^a as illustrated in Figure 3.

Modifications of the structure herein disclosed may be resorted to without departing from the spirit of the invention or the scope thereof as defined by the appended claims.

What is claimed is:

1. A tube end abrading device comprising a rotatable abrading wheel, an arm pivoted with respect to said wheel, a mandrel rotatably and slidably mounted on the free end of said arm for carrying a tube end positioned on said mandrel into engagement with said wheel, a hinge joint in said arm permitting the mandrel to be inclined either toward or away from said wheel, and adjustable means for limiting the inclination of the mandrel to align either of oppositely bevelled ends on said tube with said wheel.

2. A device for abrading internally or externally bevelled tube ends, said device comprising a rotatable buffering wheel, a mandrel for carrying a tube end into engagement with said wheel, means pivoted with respect to said wheel for inclining said mandrel either toward or away from said wheel to align either an externally bevelled tube end or a cuffed internally bevelled tube end with respect to said wheel, a stop means for limiting the movement of said pivoted means toward the wheel to determine the beveling angle for an internal bevel, and stop means

for limiting the movement of said pivoted means away from the wheel to determine the beveling angle for an exterior bevel.

3. A device of the character described comprising a buffing or abrading wheel, means for rotatably carrying an article to be buffed into engagement with said wheel, and means including an arm pivoted to swing toward and from said wheel and a shaft 10 hinged to said arm to swing toward and from said wheel for aligning said carrying means in either of oppositely inclined positions with respect to said wheel, whereby either of oppositely bevelled surfaces of the article may be buffed.

4. A device for buffing tube ends, said device comprising a rotatable buffing wheel, an arm pivoted with respect to said wheel, and a mandrel slidably journaled on the free end 20 of said arm for carrying a tube end positioned on said mandrel into engagement with said buffing wheel.
